UNITED STATES PATENT OFFICE

ROBERT J. BARTHOLOMEW, OF GERMANTOWN, PENNSYLVANIA, ASSIGNOR TO FLETCHER WORKS, INCORPORATED, OF PHILADELPHIA, PENNSYLVANIA, A CORPORATION OF PENNSYLVANIA

SPINDLE SWING BRACKET

Application filed January 3, 1931. Serial No. 506,481.

This invention relates to an adjustable swing spring for effecting the adjustment of the spring which holds the spindle against the belt in a spinning machine.

5 One of the objects of the invention is to provide an adjustment whereby a uniform twist will be obtained in the operation of the machine. In such machines the spindles are driven by the frictional contact of the 10 whorl against the driving belt and speed is a function of the contact pressure. A comparatively heavy pressure of course will allow very little slippage whereas a light pressure allows more slippage. The take-up 15 rolls are driven at a constant ratio to the belt speed and hence it will be obvious that a variation in speed between one spindle and the next will cause a similar variation in twist of the threads being twisted or spun.

20 In the drawings accompanying this application:

Fig. 1 shows an embodiment of my invention in part sectional elevation;

Fig. 2 is a section on the line 2—2 of 25 Fig. 1;

Fig. 3 is a section on the line 3—3 of Fig. 2;

Figs. 4 and 5 are views of a modification; and

30 Fig. 6 is a fragmentary view in elevation of a spinner employing my construction.

Referring to the drawings in detail, 1 designates a spindle blade, 2 a bobbin and 3 a whorl, the whorl being driven by frictional 35 contact of the same with a driving belt 4.

The spindle base is carried in a swing bracket designated 6, which is mounted for movement about a swing stud 7 secured to the rails 8 and 9. The bracket 6 is under 40 spring tension, the spring being shown at 10, to hold the whorl 3 in driving contact with the belt 4.

The present invention is directed to the arrangement of this spring, means being provided 45 whereby the tension in the spring may be adjusted so that all the whorls in the machine may be held against the driving belt with the proper pressure to insure the same speed in all the spindles. To this end, 50 therefore, the spring 10 is coiled about the

swing stud 7 and one end is fastened to the bracket as shown at 11, while the other end is inserted in an adjusting collar 12 as shown at 13. This adjusting collar is mounted on the swing stud 7 as will be seen from Fig. 1, for instance. By turning this collar on the stud 7 the tension in the spring 10 may be varied. The collar is held in adjusted position by a set screw 14 which is mounted in a bracket 15 provided for that purpose on the swing bracket. 55

It will be understood of course, as illustrated in Fig. 6 that in a machine there are a plurality of the structures above described and that by providing an individual adjustment for each swing spring the pressure of the whorls 3 against the driving belt may be regulated with great accuracy so that the spindles will be driven at the desired speed. 60 65 70

In the modification shown in Figs. 4 and 5, the swing bracket is designated 6', the swing stud 7', this stud being mounted in a sleeve S on a bracket 15 adapted to be secured to the rails 8 and 9. The sleeve S is provided with retaining lugs 16 and the swing bracket 6' with a lug 17 adapted to engage one or the other of the retaining lugs 16 thereby preventing lifting of the swing bracket off the stud when a bobbin is being removed from the spindle blade. Surrounding the sleeve S is a spring 10' one end of which as shown at 11' is attached to the bracket 6', the other end of the spring being attached to an adjusting collar 12'. This collar surrounds and cooperates with a collar 18 rigid with the sleeve S. The collars 12' and 18 have corrugated or other type of irregular adjacent faces to lock the collar 12' against accidental rotation with respect to the fixed collar 18. These collars with their corrugations or irregular surfaces take the place of the set screw 14 of the first embodiment of my invention. 80 85 90

It will be seen from the foregoing that in both embodiments of my invention I have provided means for adjusting the pressure of the whorl on the driving belt whereby the spindles will be driven at the proper speed. 95

It will be appreciated also that both em- 100

bodiments described provide for frictionally holding the parts in adjusted position, and that in the embodiment of Figs. 4 and 5 the construction is such that accidental displacement of the swing when removing a bobbin from the spindle blade is prevented.

It is to be understood that changes may be made in the details of construction and arrangement of parts within the purview of my 10 invention.

What I claim is:—

1. A machine of the class described comprising a plurality of spindles, a whorl for each spindle, a driving belt common to said 15 whorls, a swing bracket for each spindle, a spring for each bracket for holding said whorls in contact with said belt, said springs being adjustable independently to effect independent adjustment of the pressure of said 20 whorls against said belt.

2. In a machine of the class described comprising a plurality of spindles, a whorl for each spindle, a driving belt common to said whorls, a swing bracket for each spindle, a 25 spring for each bracket for holding the brackets in position to effect driving engagement of the whorls with said belt, and means for adjusting said springs independently to vary the position of the corresponding swing 30 bracket to effect a corresponding change in the pressure of the whorls against said belt.

3. In a machine of the class described the combination of a spindle swing bracket, a spring for the bracket, and an adjustable 35 collar to which the spring is attached for adjusting said spring.

4. In a machine of the class described the combination of a spindle swing bracket, a spring for the bracket, a collar for adjusting 40 said spring, and frictional means for holding the collar in adjusted position.

5. In a machine of the class described the combination of a spindle swing bracket, a mount for the bracket, a spring on said 45 mount, an adjusting collar on said mount, and a spring for said bracket, one end of the spring being attached to the bracket and the other end to the collar, and friction means for holding the collar in adjusted position on 50 said mount.

6. In a machine of the class described the combination of a spindle swing bracket, a mount for the bracket, a spring for the bracket, one end of said spring being connected 55 to the bracket, an adjusting collar to which the other end of the spring is connected, and means affixed to the bracket and frictionally engaging the collar for holding the collar in adjusted position.

7. In a machine of the class described the combination of a spindle swing bracket, a mount for the bracket, a spring for the bracket, one end of said spring being connected to the bracket, an adjusting collar to 65 which the other end of the spring is con-

nected, and a second collar rigid with said mount, said collars having engaging faces whereby the adjusting collar is held in adjusted position.

8. In a machine of the class described the combination of a spindle swing bracket, a mount for the bracket, a spring for the bracket, one end of said spring being connected to said bracket, an adjusting collar on said mount to which the other end of the spring is connected, a second collar fixed on said mount telescoped by the first collar, the adjacent contacting faces of said collars being corrugated to hold the adjusting collar in adjusted position.

This specification signed this 27 day of Dec., 1930.

ROBERT J. BARTHOLOMEW.
